UNITED STATES PATENT OFFICE.

HERMAN E. S. CHAYES, OF NEW YORK, N.Y.

ARTIFICIAL TOOTH.

No. 885,018.

Specification of Letters Patent. Patented April 21, 1908.

Application filed March 11, 1907. Serial No. 361,663.

To all whom it may concern:

Be it known that I, HERMAN E. S. CHAYES, a citizen of the United States, and a resident of the borough of Manhattan, city and State of New York, have invented certain new and useful Improvements in Artificial-Teeth Devices, of which the following is a specification.

My invention relates to an improved means for securing an artificial tooth, consisting of a facing of enamel or other suitable material in the likeness of a tooth, to a backing of metal or other suitable material, which backing is anchored or secured in the mouth according to any well known means.

The aforesaid means for securing the facing to the backing are such as to effectually lock these parts together against lateral and unintentional vertical motion on each other.

The devices are furthermore quickly and easily operated. They do not to any extent weaken the facing member and they are cheap to manufacture. Moreover by a certain modification hereinafter described I make the connection between the facing and the backing adjustable vertically so that the facing, which as stated is in the semblance of a tooth, may be adjusted vertically relative to the gum to conform to any peculiar condition or characteristic thereof.

Some of the specific forms which my invention may take are illustrated in the accompanying drawings, wherein

Figure 1 is a rear perspective view of a facing embodying my invention; Fig. 2 is a front perspective view of a backing adapted to cooperate with said facing; Fig. 3 is a vertical mid-section of the facing and backing showing the facing about to be pressed upwards into locked position on the backing; Fig. 4 shows the same parts in their said locked position; Fig. 5 shows a modification in the facing consisting of the use of two transverse pins instead of one; Fig. 6 is a modification of the backing consisting in the adjustable nature of the lugs relative to the backing; Figs. 7 and 8 are enlarged perspective views of the lugs shown in Fig. 6 but detached for the purposes of illustration from the backing plate.

Describing now the specific forms of my invention illustrated, it will be understood that the backing 1 is anchored in the mouth in the space left by the missing tooth in any well known manner, as for example, by securing same on each side to suitable crowns

on the adjacent teeth. This backing may be of any suitable metal. Projecting from it (see Figs. 2, 3 and 4) are lugs 2 and 3 which coact as hereinafter described with the facing to secure it rigidly to the backing. This facing, designated 4, takes the form of a tooth and is made of enamel or other suitable material. The facing is surfaced on its rear side to rest against the front surface of the backing. It is also formed on its rear side with a cavity 5 the bottom of which is formed with an elevated or raised portion 6 and the lower end of which as seen best in Figs. 3 and 4 is undercut at 7. Bridging the cavity 5 transversely relative to the facing is a pin or strip 8 preferably of metal.

The entire facing together with its cavity will ordinarily be made by casting the same in a suitable mold and the pin 8 may be cast integrally into place in the same operation.

The lug 2 on the backing is preferably made of springy material. It preferably also has the arched form shown with its free end recurving towards the front face of the backing and the extremity thereof curled upward to permit the pin 8 of the facing readily to pass under the free end of the lug as it must when the facing is forced into locking position on the backing. In illustration of the foregoing Fig. 3 shows in section the facing 4 in position against the backing 1 and about to be raised vertically with its pin 8 just beginning to force its way under the free end of the spring lug 2. Fig. 4 shows the same parts after the facing has been forced upwards into its locking position with the spring lug 2 embracing the pin 8.

As stated the lug 2 is preferably formed of springy material in order that it may coact with the pin to secure the facing more tightly to the backing. To additionally effect this same result the bottom of the cavity 5 may be formed with an elevation 6 adapted to contact with the lug 2 during the operation of pressing the facing into locking position on the backing and thereby press it toward the backing and so cause the lug, after the pin 8 has entered within its arch, to press tightly against said pin and consequently lock the facing rigidly to the backing.

The lug 3 of the backing is received into the undercut portion 7 of the facing when the parts have been pressed into locked position and by wedge action holds these parts in locking contact.

The lugs 2 and 3 are preferably just wide

enough to be received between the sides of the cavity 5. The facing is therefore effectually secured against lateral motion on the backing while the locking devices prevent 5 unintentional vertical displacement.

Instead of providing an under-cut portion 7 in the facing to receive the lug 3, I may provide a second pin 9 bridging the cavity (see Fig. 5). In this modification the lug 2 co- 10 acts as previously with the upper pin 8 while the lug 3 coacts with the lower pin 9 by arching about it in somewhat analogous fashion.

To give the lug 3 additional locking action on the facing, I provide a projection 13 from 15 said lug which fits into an opening or recess 14 corresponding thereto in the facing—see Figs. 1, 3 and 4.

Figs. 6, 7 and 8 show a modification in which the lugs 2 and 3 are adjustable on the 20 backing. In this modification the backing is formed with slots 10 and the lugs with lateral ears 11 adapted to extend through the slots to secure the lugs to the backing but at the same time permit them to have up and 25 down adjustment relative both to the backing and to each other.

In using my artificial tooth devices the 30 backing will be anchored suitably in the mouth. The cavity in the facing will then be filled with a cementing material 12 and then pressed into locked position on the backing and the cement having hardened, the tooth facing will be securely fixed in place.

35 Conditions not infrequently arise in practice where the facing and the backing with fixed lugs cannot be adapted to the particular mouth to bring the tooth into the exact location desired relative to the gum;—in this 40 event the backing with the adjustable lugs will be employed to adjust the facing into the exact position required. After the lugs have been adjusted on the backing in proper position, they are soldered fixedly thereto. The 45 use and operation of this modification is otherwise similar to that described for the facing with the nonadjustable lugs.

Having thus described my invention, what I claim is:—

50 1. In an artificial tooth device, the combination of a backing having a lug adapted to be received into a cavity in a facing and to hook around a pin across the cavity; said facing; and said pin.

55 2. In an artificial tooth device, the combination of a backing formed with a lug of springy material; a facing having a cavity adapted to receive said lug; and a pin across said cavity adapted to be received and held 60 by spring action under said lug.

3. In an artificial tooth device, the com-

bination of a backing formed with a lug of springy material; a facing having a cavity adapted to receive said lug; a pin across said cavity adapted to be received and held by 65 spring action under said lug; and a part on the facing adapted to contact with the lug and press the same against the pin.

4. In an artificial tooth device, the combination of a backing having a lug; a facing having a cavity adapted to receive said lug; a pin across said cavity, adapted to be received between the lug and the backing when the facing is slid longitudinally in contact with the backing; and a part on the facing 75 adapted to contact with the lug and press the same against the pin.

5. In an artificial tooth device, the combination of a backing having a lug; a facing having a cavity adapted to receive said lug; a pin across said cavity, adapted to be received between the lug and the backing when the facing is slid longitudinally in contact with the backing; a part on the facing adapted to contact with the lug and press the same 80 against the pin; a second lug on the backing adapted to be received in a cavity in the facing and to extend under and contact with an under-cut portion of said facing; and said under-cut portion. 85

6. In an artificial tooth device, the combination of a backing having a lug; a facing having a cavity adapted to receive said lug; a pin across said cavity, adapted to be received between the lug and the backing when the facing is slid longitudinally in contact with the backing; a part on the facing adapted to contact with the lug and press same 90 against the pin; a second lug on the backing adapted to be received in a cavity in the facing and to extend under and contact with a fixed part on said facing. 95

7. In an artificial tooth-device, the combination of a backing having a lug movably supported thereon and adapted to be firmly secured thereto when properly spaced, said lug being adapted to be received into a cavity in a facing and to hook around a pin across the cavity; said facing; and said pin. 100

8. In an artificial tooth device, the combination of a backing; a lug on the backing, which lug has a projection thereon; a facing having a cavity adapted to receive the lug, a wall of said cavity being recessed to receive the projection on the lug. 105

In witness whereof, I have signed my name to the foregoing specification in the presence of two subscribing witnesses.
